UNITED STATES PATENT OFFICE.

THOMAS BURTON SHANAHAN, OF ROCHESTER, NEW YORK.

NONGLARE REFLECTOR FOR HEADLIGHTS.

Application filed January 15, 1921. Serial No. 437,547.

To all whom it may concern:

Be it known that I, THOMAS B. SHANAHAN, a citizen of the United States, and a resident of Rochester, in the county of Monroe and State of New York, have invented a certain new and useful Nonglare Reflector for Headlights, of which the following is a specification.

This invention has for its object the production of a non-glare reflector for headlights of motor vehicles which is particularly simple in construction, economical in manufacture and highly efficient and durable in use and it consists in the novel features hereinafter described and claimed.

In describing this invention, reference is had to the accompanying drawings in which like characters designate corresponding parts in all the views.

20 Figure 1 is a face view of this reflector. Figures 2 and 3 are sectional views taken respectively on lines 2-2, and 3-3, Fig. 1.

Figure 4 is a rear elevation of this attachment, the same being shown as applied 25 to the lamp.

Figure 5 is a transverse sectional view through a headlight provided with my invention.

This non-glare reflector for headlights 30 comprises a member which is concave and spherically curved in two directions, the arcs of the concavity being of different radii in lengthwise and transverse directions whereby the reflector is longer than it is wide and the arc of the longest lengthwise curve is greater than the arc of the longest transverse curve so that the reflector is composed of substantially upper and lower spherical sections of like curvature and an intermediate zone of a different spherical curvature in a direction lengthwise and crosswise of the reflector.

40 1 designates the reflector which is longer from its upper to its lower end than between its sides as shown in Fig. 1.

As seen in Figs. 2 and 3, the arc of the greatest lengthwise curve midway between the sides of the reflector is greater than the arc of the transverse curve, Fig. 3, midway 50 between the ends of the reflector although the edge 2 of the reflector is in a plane. The differences in these curves provide a reflector which has upper and lower sections

3, 4 and an intermediate zone 5 defined in Fig. 1 by dotted parallel lines, this zone 55 also being bounded at its ends by the parallel edges 6 of the reflector.

The upper section 3 is formed with an opening 7 therein for receiving the plug 8 of an incandescent electric lamp 9.

60 When the lamp is in position the parallel portions 6 of the edges come close to the sides of the lamp and hence do not cut off the rays of light from the greater portions of the main parabolic reflector 10 of the 65 headlight while the section 4 extends comparatively far under the lamp 9 and increases in distance away from the lamp or filament between the parallel portions 6 of the edges and the lower end of the reflector 70 and hence cuts off the greater portion of the lower section 10^a of the parabolic reflector of the headlight so that rays of light 75 are not reflected upwardly by this section 10^a into the eyes of pedestrians.

I am aware that there are other non-glare attachments which in some respects are similar to this but I have found that a reflector of the form here shown and described 80 produces the best results and at the same time gives a maximum light where the light is wanted.

What I claim is:

The combination with a headlight comprising a reflector, a lamp socket at the center of the reflector and an electric lamp arranged in the axis of the reflector and having a base for entering the socket, of a non-glare reflector in the form of a spoon 85 arranged below the lamp bulb, the spoon being spherically concave, and having its intermediate zone of different spherical curvature than the end zones and the upward forward edge of the spoon being inclined downwardly and forwardly on opposite sides of the bulb in a plane intersecting the axis of the reflector, the spoon being provided with an opening near one end for receiving the lamp base, substantially as and for the purpose described.

90 In testimony whereof, I have hereunto signed my name at Rochester, in the county of Monroe, and State of New York, this 12 day of September, 1920.

THOMAS BURTON SHANAHAN.
